ATTORNEY

UNITED STATES PATENT OFFICE.

ULYSSES G. HOUSTON, OF VALPARAISO, INDIANA.

PLANETARIUM.

SPECIFICATION forming part of Letters Patent No. 367,104, dated July 26, 1887.

Application filed January 10, 1887. Serial No. 223,861. (No model.)

To all whom it may concern:

Be it known that I, ULYSSES G. HOUSTON, a citizen of the United States, and a resident of Valparaiso, in the county of Porter and State of Indiana, have invented new and useful Improvements in Astronomical Apparatus, of which the following is a specification, reference being had to the accompanying drawings, two sheets illustrating the invention, in which—

10 Figure I is a plan or top view of an apparatus embodying my invention. Fig. II is a sectional view on line x , Fig. I; Fig. III, a top or plan view of the planet-holder for the earth removed from the rotating disk surrounding it. 15 Fig. IV is a sectional view on line z , Fig. I; Fig. V, a view of the planet earth as would be seen at Fig. I by looking in the direction indicated by dart y . Fig. VI shows the earth in position in its holder as when the sun is 20 vertically over the equator and the holder removed from the rotating plane. Fig. VII shows the earth in its holder in position as when in summer solstice.

The purpose of this invention is to provide 25 an astronomical apparatus which shall be much simpler and less expensive than those now in use for illustrating the movements and positions of the planets of our solar system, and one which will serve well the purpose of primary education. In reducing my invention to practice I have found that it is much simpler to represent the planets on a plane which rotates around a body representing the sun, and to represent the satellites as moving on the 30 same plane as the planets.

The mechanism employed is as follows:

A represents a table of any desired size, to serve as a support for the devices hereinafter mentioned.

40 B represents a circular plane, which is made of wood or other suitable material, and of such diameter as may be chosen as the planet-field, and it is centrally pivoted to the table A by a post, C, which projects down from the body F, representing the sun, and serves also as a pivot for a pulley, D.

Affixed to the post C, and placed above the rotating plane B, is a three-grooved pulley, E, and between this pulley and the sun F is a 45 small pulley, also affixed to the post C.

Pivoted to the table A by means of a post, L H, is a pulley, I, of the same size and kind as pulley D, and to this post, above the bed A, are affixed pulleys J and K. In the plane B are formed vertically six holes, and in them are 55 closely fitted what I term "planet-holders," which are cylindrical sections c , of metal, projecting far enough above the plane to form pivots for rings N, X, V, T, R, and P to turn on, the top portions of the cylinders being 60 flanged at a to hold the rings on. In these holders spherical bodies M W U S Q O are placed, and holes 8 8 are formed through the plane B, in which are placed the two planets nearest to the sun. All the spherical bodies, 65 representing the eight primary planets, except the earth, rest on the table A, so that when the plane B is rotated they will travel on the table and rotate. The north pole of the earth is shown at b , and an equatorial bearing, through 70 the earth is shown at n , Figs. I and V. The flange a supports the bearing n , and consequently holds the earth M suspended on the holder c . (See Figs. III, V, VI, and VII.) The south pole of the earth passes through a slot- 75 ted plate, d , affixed to the holder c , and into an eccentric groove, e , formed in the top face of the table A, the groove being shown twice in section at Fig. II, and its position indicated by dotted line, Fig. I. A staple, m , is driven 80 into the ring N, and the bearing n passes through it, so that when the ring is turned the earth will be turned on its polar axis to represent night and day. Vertically through each ring pivoted to the holders c are formed one or more 85 holes, 1, corresponding to the number of satellites or moons the particular planet within said holder has, and in these holes are placed spherical bodies, which rotate by traveling on the plane B—as, for instance, the Earth M has 90 one moon, 7; Saturn W has eight moons, 2; Mars U has two moons, 3; Jupiter S has four moons, 4; Uranus Q has six moons, 5, and Neptune has one moon, 6.

Y represents Venus, and Z represents Mercury. A band, h , is placed on pulley E and passes around the four rings T, V, X, and N, and rotates them, carrying the moons around their respective planets. Single belts, however, may be employed for each of the rings 95 100

mentioned. A crossed belt, *i*, on pulley E and ring R rotates the latter, and a cross-belt, *j*, drives ring P. A belt, dotted lines *g*, Fig. I, is put over pulleys K, to carry bodies representing comets toward the sun. This construction is such that power applied to rotate the sun in the direction indicated by dart 10, Fig. I, will rotate the rings M W V T in the same direction and rotate the rings R P in the opposite direction, coinciding with the rotation of the planets within the respective ring relative to the sun F. The rotation of the sun will bring the earth into the position of winter solstice, and bring it into summer solstice when it is brought around to the opposite side of the sun; and when the earth is brought to the point where the dotted line *g* crosses the dotted line *h* over the eccentric groove *e*, there will be vernal and autumnal equinoxes. It will be understood that in this limited space the comparative sizes and distances of the planets cannot be illustrated, but that when a large apparatus is constructed the proper relation of parts can be more nearly approximated. In such case the asteroids between the planets Mars and Jupiter can be illustrated, together with much other astronomical data. In small

library apparatus the sun can be turned by hand; but in large apparatus power may be applied to the post C of pulley D, which, being connected by a cross-band, *f*, with the pulley I, will give the proper movement to the devices.

Having thus described my invention, what I claim, and desire to secure by Letters Patent, is--

1. The table A, provided with the eccentric groove *e*, in combination with the rotating plane B, the holders *c a*, extending through the plane, the rings pivoted to the holders, and the earth-holder provided with the slotted plate *d*, and the earth provided with a north and south pole and with equatorial bearing *n*, and one or more rings provided with a staple, *m*, and suitable means, *h i j E*, for rotating the rings, as specified. 35

2. The combination of the plane B with the cylindrical planet-seats *c a* and rings with holes 40 1 through them for carrying the moons, as specified. 45

ULYSSES G. HOUSTON.
